DESIGN FOR A BLOODLESS CIRCUMCISION CLAMP

Aaron A. Goldstein, Buffalo, N. Y.

Application March 16, 1939, Serial No. 83,613

Term of patent 14 years

To all whom it may concern:

Be it known that I, Aaron A. Goldstein, a citizen of the United States, residing at Buffalo, in the county of Erie and State of New York, have invented a new, original, and ornamental Design for a Bloodless Circumcision Clamp, of which the following is a specification, reference being had to the accompanying drawing, forming part thereof.

Fig. 1 is a perspective view of a bloodless circumcision clamp showing my new design.

Fig. 2 is a top plan view thereof.

Fig. 3 is an end elevation thereof.

The characteristic features of my design reside in the specific configuration of the top plate shown.

I claim:

The ornamental design for a bloodless circumcision clamp, as shown and described.

AARON A. GOLDSTEIN.
